CLAIM

The ornamental design for a cookpot as shown and described.

DESCRIPTION

FIG. 1 is a perspective view of a cookpot in accordance with my design;

FIG. 2 is a front elevational view of the cookpot of FIG. 1; FIG. 3 is a rear elevational view of the cookpot of FIG. 1; FIG. 4 is a left side elevational view of the cookpot of FIG. 1;

FIG. 5 is a right side elevational view of the cookpot of FIG. 1;

FIG. 6 is a top plan view of the cookpot of FIG. 1; FIG. 7 is a bottom plan view of the cookpot of FIG. 1; and, FIG. 8 is a cross-sectional side view of the cookpot of FIG. 1, taken at section line 8-8 as shown in FIG. 5.

The broken lines having consistent dash lengths (dash-dash-dash) represent portions of the cookpot that form no part of the claimed design.
